UNITED STATES PATENT OFFICE.

AUGUST KEHM, OF CHICAGO, ILLINOIS.

DESIGN FOR A REFRIGERATING-RADIATOR.

59,229.

Specification for Design.

Patented Oct. 4, 1921.

Application filed January 25, 1919. Serial No. 273,162. Term of patent 3½ years.

To all whom it may concern:

Be it known that I, AUGUST KEHM, a citizen of the United States, residing at Chicago, in the county of Cook and State of Illinois, have invented a new, original, and ornamental Design for Refrigerating-Radiators, of which the following is a specification, reference being had to the accompanying drawings, forming a part thereof, wherein—

Figure 1 is a front elevation of the radiator,

Fig. 2 is a plan view of the same partly broken away and with the members thus exposed shown in section, and

Fig. 3 is an end elevation of the radiator.

I claim:

The ornamental design for a refrigerating radiator, as shown.

AUGUST KEHM.
